UNITED STATES PATENT OFFICE.

EARL EDMUND THOMPSON, OF WINNIPEG, MANITOBA, CANADA.

SHEAF-LOADER.

1,227,343.

Specification of Letters Patent.

Patented May 22, 1917.

Application filed June 29, 1916. Serial No. 106,667.

To all whom it may concern:

Be it known that I, EARL EDMUND THOMPSON, of the city of Winnipeg, in the Province of Manitoba, Canada, have invented certain new and useful Improvements in Sheaf-Loaders, of which the following is the specification.

The invention relates to improvements in sheaf loaders and particularly to what is commonly known as the "pick-up" part or "nose" of a sheaf loader and the object of the invention is to provide a simply constructed, durable and efficient pick-up for a sheaf loader which can be readily adjusted to accommodate working conditions and which has but few parts in its make-up, and those all arranged so that they can be readily assembled and at small cost.

With the above principal object in view the invention consists essentially on the arrangement and construction of parts hereinafter more particularly described and later pointed out in the appended claims, reference being had to the accompanying drawings in which:—

Figure 1 represents a side view of a sheaf loader equipped with my invention.

Fig. 2 represents an enlarged detailed face view of the outer side of one of the pick-up chain wheels showing the controlling parts, certain adjacent parts being shown in vertical section.

Fig. 3 represents an end view of the forward end of the nose, the central portion thereof being broken away.

Fig. 4 represents an enlarged detailed vertical sectional view through the front end of the machine, the section being taken to show the manner in which the joint is formed between the nose and the inclined elevator.

Fig. 5 represents a side view of one of the trip carrying plates.

In the drawings like characters of reference indicate corresponding parts in the several figures.

1 represents a main frame suitably mounted on front and rear sets of carriage wheels 2 and 3. On this frame I erect suitably braced, varying length opposing pairs of uprights 4, 5, 6 and 7 which uprights carry an inclined conveyer 8 and side shields indicated at 9.

The driving shaft of the conveyer is indicated at 10, this being suitably mounted in the bearings carried by the uprights 4.

The shaft 10 is supplied with a chain wheel 11 which is driven through any suitable form of driving connection indicated at 12 from one of the rear carriage wheels 3. 60

Immediately adjoining the upper end of the inclined conveyer I locate a side chute 13 to receive sheaves from the inclined conveyer and in a suitable location on the side of the machine I locate a platform 14 and 65 an attendant's seat 15.

I have not considered it necessary to give a detailed description of the above parts of the machine as they are, with the exception of the conveyer, found on a great many machines already patented. The particular part which I consider new and for which I wish to obtain Letters Patent is the nose or pick-up part of the sheaf loader and as this is closely associated with the conveyer I require that the conveyer be built in a certain manner as shortly described to accommodate the pick-up which is indicated in a general manner by the reference numeral 16. 70

To the side uprights of the machine I secure permanently parallel upper and lower opposing pairs of angle irons 17 and 18 which have their horizontal flanges turned inwardly. The lower ends of these angle irons terminate in a location more or less directly above the front wheels where they are secured permanently to a pair of opposing side plates 19 and 20 which side plates carry a cross shaft 21 from which I swing the nose or pick-up. 75 90

The nose or pick-up embodies in its structure upper and lower opposing pairs of angle iron bars 22 and 23 connected by side bars 24 and 25 and having their horizontal flanges turned inwardly. To the upper ends of these latter bars I secure inner plates 26 and 27 disposed immediately to the inner sides of the plates 19 and 20 and swung pivotally from the shaft 21. According to this construction the nose is pivotally swung from the shaft and in constructing the machine the adjacent ends of the angle bars 22 and 23 and those 17 and 18 must be spaced apart so that in the movement of the nose they will clear. 95 100

Between the top angle bars 17 I locate a cross carrier 28 which is permanently secured to the under side of the inturned flanges of the angle irons. The lower end of this cross carrier projects beyond the lower ends of the angle irons 17 (see Fig. 4) and overlaps the upper end of a second 105 110

cross carrier 29 permanently secured to the underside of the in-turned flanges of the angle irons 22.

From the above it will be obvious that 5 I have really a continuous cross carrier from the lower end of the nose to the top end of the conveyer, which carrier is broken only (as shown in Fig. 4) to allow for the movement of the nose when adjusted as later 10 described. The carrier is preferably formed from sheet metal. The nose is supplied with similar side shields 30 and 31 which are secured to the bars 24 and 25 and are really a continuation of the top shields 9. 15 In this connection it is necessary to have the upper ends of the shields 30 and 31 pass to the inner sides of the shields 9. The lower end of the nose carries a pair of similar permanent trip carrying side 20 plates 32 and 33 which are permanently bolted to the angle irons 22 and 23 and the said side plates provide the bearings for the lower conveyer shaft 34 which it will be noticed projects beyond the side plates. 25 On the platform I locate a hand lever 35 fitted with the usual hand latch and detent 37 operating over a quadrant 38 secured to the platform. This lever is secured by a pair of links 39 and 40 to a crank 41 secured to the end of the shaft 21 and the 30 crank is in turn connected by means of a tie rod 42 to the projecting end of the shaft 34.

From the above construction it will be 35 obvious that one by manipulating the hand lever can raise or lower the forward end of the nose and accordingly vary its height from the ground.

The shafts 10 and 34 are provided in the 40 ordinary way with pairs of chain wheels 43 and these chain wheels carry endless conveyer chains 44 and 45 which lie normally on the in-turned flanges of the angle irons and are provided at suitable distances 45 throughout their length with connecting cross slats 46.

These chain wheels, chains and cross slats form the endless conveyer hereinbefore referred to and in connection with the chains 50 it is to be understood that there is sufficient slack in them to allow for the slight tightening which will occur in the adjustment of the nose or pick-up. The lower pair of chain wheels 43 carry in the present instance 3 55 equi-spaced rotatably mounted cross shafts 47, 48 and 49 which cross shafts are supplied each with a set of spaced prongs 50. Between the outer sides of the latter chain wheels 43 and the plates 32 and 33 and on 60 opposite ends of the shaft 47, 48 and 49 I locate rollers 51, 52 and 53 which rollers are permanently secured to the shaft and between the rollers and the outer faces of the wheels 43 and on the shafts I have 65 placed similar catch blocks 54, 55 and 56,

which blocks extend from the shafts in the opposite directions to the prongs.

Associated with the blocks I employ controlling dogs 57, 58 and 59 which are pivotally secured as indicated at 60 to the 70 outer faces of the chain wheels 43. The dogs are all similarly constructed being each supplied with a pair of spaced stops or lugs 61 and 62 and having their inner sides slightly arched, as shown at 63 to 75 form a guide. The dogs are normally pressed toward the catch blocks 54, 55 and 56 by the action of spiral springs 64 mounted on pins 65 extending from lugs 66 carried by the chain wheels, it being understood 80 that the pins are slidably entered in openings or holes bored in the back faces of the controlling dogs. Each of the controlling dogs is provided with a heel 67 which, in the turning of the chain wheels 85 43, is designed to engage with and drag over an inwardly extending catch piece 68 projecting inwardly from each of the side plates 32 and 33. The plates 32 and 33 are fitted also with inwardly extending short 90 length roller tracks 69 and 70, these tracks being arranged concentric to the shaft 34 and a different radii so that in the turning of the chain wheels the rollers 51, 52 and 53 will be rolled by frictional contact with the track 70 in one direction and by frictional contact with the track 69 in the opposite direction.

The particular positions which the catch piece 68, the roller tracks 69 and 70, the 100 controlling dogs 57, 58 and 59 and the catch blocks 54, 55 and 56, have in respect to one another is best shown in Fig. 2 where it will be observed that the upper prongs are locked in the upright position by the lugs 105 61 and 62 of the dog 58, the roller 52 is about to engage with the roller track 70 as is also the catch piece with the heel 67 of the dog 58, the roller 51 is rolling on the track 69 and the lugs 61 and 62 of the 110 dog 57 are clear of the catch block 54 and the catch block 56 is locked by the lugs of the dog 59.

By closely studying this figure it will be observed that as the prongs are being 115 passed from a lowermost position to an upper position, which is actually the interval when they are picking up the sheaves, they are positively locked against rotation by the lugs of the dogs engaging the catch blocks. However, after the sheaves have been brought up by the prongs to the position where they are delivered on to the conveyer it will be obvious that the catch piece 68 will trip the up-coming dog by engagement with the heel thereof and unlock the catch block and that almost coincident with this action the roller of the then top shaft, will be rolled by engagement with the tracks 120 70 to throw back the prongs and let them 125 130

clear both the slats of the conveyer and the lower end of the cross carrier 29.

Further it will be apparent that after the prongs have been thrown back to clear the aforesaid parts they will again be thrown ahead by the rollers engaging with the track 69 and will be brought by the action of this track again into the original sheaf catching position, in which position they are automatically locked by the lugs of the adjacent dog, this occurring coincident with the clearance of the roller from the track 69.

From the above it will be obvious that the prongs are at all times positively under control and that they are positively locked when the sheaf is being picked up and delivered to the conveyer.

What I claim as my invention is:—

1. A sheaf loader pick up, in combination with an endless conveyer and chain wheels comprising a sheaf loader pick up comprising a pair of chain wheels, spaced cross shafts rotatably mounted in the pair of chain wheels, a set of prongs extending from each of the cross shafts, similar rollers secured to the ends of the cross shafts, an adjacent conveyer, tracks carried by the lower end of the conveyer frame and engageable with the rollers and adapted to rotate the rollers, one in the forward direction and the other in the reverse direction and means for locking the shafts against rotation during the interval that the rollers are disengaged from the tracks.
2. A sheaf loader pick up in combination with an endless conveyer including a frame, and chain wheels for the conveyer, comprising a sheaf loader pick up comprising a pair of chain wheels, spaced cross shafts rotatably mounted in the pair of chain wheels, a set of prongs extending from each of the cross shafts, similar rollers secured to the ends of the cross shafts, an adjacent conveyer, side plates permanently secured to the lower end of the conveyer frame, short length roller tracks extending inwardly from the side plates and disposed at different radii and adapted in the rotation of the chain wheels to engage with the rollers and effect, one a reverse rotation of the rollers and the other the forward rotation of the rollers and means for locking the shafts against rotation during the interval that the rollers are clear of the tracks.
3. A sheaf loader pick up in combination with an endless conveyer including a frame, and chain wheels for the conveyer, com-

prising a sheaf loader pick up comprising a pair of chain wheels, spaced cross shafts rotatably mounted in the pair of chain 60 wheels, a set of prongs extending from each of the cross shafts, similar rollers secured to the ends of the cross shafts, an adjacent conveyer, side plates permanently secured to the lower end of the conveyer frame, 65 short length roller tracks extending inwardly from the side plates and disposed at different radii and adapted in the rotation of the chain wheels to engage with the rollers and effect, one a reverse rotation of 70 the rollers and the other a forward rotation of the rollers, catch blocks secured permanently to the shafts, pivoted spring pressed dogs carried by the chain wheels and normally engaging with the catch blocks to 75 lock the same against movement and means for tripping the dogs to release the catch blocks at the instant the rollers engage the roller tracks.

4. A sheaf loader pick up in combination 80 with an endless conveyer including a frame, and chain wheels for the conveyer, comprising a sheaf loader pick up comprising a pair of chain wheels, spaced cross shafts rotatably mounted in the pair of chain 85 wheels, a set of prongs extending from each of the cross shafts, similar rollers secured to the ends of the cross shafts, an adjacent conveyer, side plates permanently secured to the lower end of the conveyer frame, short 90 length roller tracks extending inwardly from the side plates and disposed at different radii and adapted in the rotation of the chain wheels to engage with the rollers and effect, one a reverse rotation of the 95 rollers and the other a forward rotation of the rollers, catch blocks secured permanently to the shafts, pivoted spring pressed dogs carried by the chain wheels and normally engaging with the catch blocks to 100 lock the same against movement, said dogs being fitted with extending heels and a catch piece extending inwardly from each of the side plates and engageable with the heels of the dogs and designed to disengage 105 the dogs from the catch block at the instant the rollers engage the tracks.

Signed at Winnipeg, this 8th day of April 1916.

EARL EDMUND THOMPSON.

In the presence of—
G. S. ROXBURGH,
ROLAND FOSTER.
